UNITED STATES PATENT OFFICE.

HANNIBAL A. KUNITZ, OF PITTSBURGH, PENNSYLVANIA, ASSIGNOR OF ONE-HALF TO
WILLIAM T. CAHOON, OF PITTSBURGH, PENNSYLVANIA.

ELECTRICAL DISPLAY DEVICE.

1,108,190.

Specification of Letters Patent. Patented Aug. 25, 1914.

Application filed May 19, 1911. Serial No. 628,324.

To all whom it may concern:

Be it known that I, HANNIBAL A. KUNITZ, a citizen of the United States, and resident of Pittsburgh, in the county of Allegheny and State of Pennsylvania, have invented a new and useful Improvement in Electrical Display Devices; and I do hereby declare the following to be a full, clear, and exact description thereof.

My invention relates to electric display devices for ornamental and advertising uses. In devices of this nature electric lights of varying types and various colors are employed to ornament and illuminate the exterior and interior of buildings, and advertising signs and the like. For the latter purpose these ornamental illuminating devices are usually arranged to be periodically electrified and put out, so as to call the attention of the public to the illuminated advertising matter in connection with which they are used. To accomplish this result some type of electric make and break device, termed an "electric sign flasher" is generally employed so that the display device proper and the advertising matter are electrified alternately or according to some desired plan so that the entire advertising sign will be beautified and the attention of the public drawn thereto.

The object of my invention is to greatly improve the ornamental effects attainable in this type of device, and to produce a display the varying form and color of which continually changes in shape and shade for a long interval of time so as to produce a beautiful and striking effect.

My invention contemplates a device of this character comprising an electric light tube, preferably of the Geissler or vacuum tube type, and preferably a plurality of such tubes being arranged in series in proximity to each other, and means for simultaneously revolving said tube or tubes and otherwise moving or preferably rotating the same so as to produce a variegated light effect.

My invention also consists in providing rotating and revolving mechanism actuating a disk frame on which the light-tubes are carried and forming in itself part of the electric circuit by which the tubes are illuminated. It also consists in a number of other features of construction and combination of

parts as hereinafter more specifically described.

On the accompanying drawings Figure 1 is a front elevation of a display device embodying my invention. Fig. 2 is a plan view of the same. Fig. 3 is a vertical section of the same on line 3—3 Fig. 1. Fig. 4 is a diagrammatic plan view illustrating the essential features of the electrifying system employed. Fig. 5 is a longitudinal section through one of the vacuum tubes illustrated.

The rotary disk frame 1 illustrated is mounted on a metallic shaft 2 journaled in the bearing brackets 3, 3'. The shaft 2 is driven in any suitable manner as through the pulley 4 and leather belt 5 leading to any suitable source of power, such as a motor. The light-tubes 7 (as shown diagrammatically in Fig. 4) are rotatably mounted on the disk frame 1. I preferably employ a considerable number of such tubes 7, each tube varying somewhat in form and in color of light from the others. In Figs. 1 to 3 I have illustrated four of such tubes, namely, the tubes 7^a, 7^b, 7^c, 7^d, separately mounted, and the tube 7^d, which is mounted to rotate with the tube 7^d, making five in all. The tubes are carried on rotary disks 8^a, 8^b, 8^c, and 8^d, respectively. The aforesaid disks are carried respectively by the metallic shafts 9^a, 9^b, 9^c and 9^d each journaled in a bearing 10 in the form of a bushing of brass, iron or other conducting material mounted in the disk 1' of the disk frame 1, which is preferably of fiber, wood or like insulating material. Each of the disks 8 is also preferably of insulating material and is provided with the metallic bushing or hub 11 fastened to its respective shaft 9^a or 9^b, etc. The tubes 7 are preferably Geissler tubes, by which I mean vacuum tubes provided with a positive and negative pole or electrode, and so constructed as when electrified, to cast a well defined filamentous light which preserves its shape and definite extent to a great degree when rotated even at a high rate, as distinguished from a mere carbon filament or other similar type of lamp, the light from which when rotated at a moderate rate becomes indefinite and blurred so as to appear merely as a spot or circle. It will be understood, however, that my invention is not limited to the use of any

specific form or type of lamp or light tube, and that the term "light-tube" as used herein and in the accompanying claims is intended merely to designate a type of light 5 or lamp which is adapted to produce the well known illuminating effects of the Geissler tube, so that the variegated and beautiful varying light effects produced by the device of my invention are obtained. The 10 said electrical tubes 7^a, 7^b, etc., are furthermore preferably so arranged that when rotated, one or more of them traverses successively part of the path passed over by another or others of the tubes. Thus, as 15 illustrated in Figs. 1 and 2, the tube 7^a is so mounted on the disk 8^a that it successively passes over part of the space S on the plan of the disk 1' which is passed over also by the tube 7^a, the mounting and rotation of 20 the said tubes to be described below permitting of this operation without the contact of the tubes. An equivalent light effect may be produced, however, by providing a longer shaft carrying the disk on which a tube is 25 mounted. Thus the tube 7^c which is illustrated as a relatively very long tube has its carrying disk 8^c mounted on a shaft 9^c which extends far enough out from the disk frame 1 to permit the rotation of the tube 7^c and 30 the tubes 7^d and 7^{d'}. It is evident that the appearance in plan view or elevation, i. e., to the eye, when the electrified light-tubes are rotated and simultaneously revolved, is 35 that of intertwining and constantly varying lines or forms of lights of different colors. The variegated colors are conveniently produced by a colored liquid carried within each tube, as 7^c and around the vacuated inner tube or snake 13, as illustrated in Fig. 5.

40 The sprocket wheel 14 of insulating material is carried fixedly on the shaft 2 and connected by means of the sprocket chain 15 to the sprocket wheel 16 splined or otherwise fastened to the short countershaft 18

45 journaled in the bearing bracket 19. The sprocket wheel 14 is formed conveniently of two disks 14' of fiber or wood separated by a central disk 14'' of fiber which is serrated at its margin to form the sprocket 50 teeth 19, a number of the other insulated sprocket wheels illustrated being similarly constructed but not specifically described, as to this feature.

55 A sprocket wheel 20 is also fastened to the shaft 18 and connected by the chain 21 to the wheel 22 rotatably journaled on the driving shaft 2. The wheel 22 is of insulating material, preferably similar in construction to the wheel 14 above described,

60 but is provided with the metallic contact face 23 on which the chain 21 meshing with the gear teeth 24 plays. Another sprocket wheel illustrated merely as another set of sprocket teeth 25 on the portion 22' of the 65 wheel 22 is connected by the sprocket chain

26 to the sprocket wheel 27 mounted on the shaft 9^a. The contact face 23 on the sprocket wheel 22 is continued at 23' so as to contact with the links of the chain 26 and transmit current through the said chain to 70 the sprocket wheel 27 of conducting material.

The disk frame 1 is constructed preferably of the two disks 1' and 12 rigidly connected by the screw bolts 50 extending 75 through the bracing studs 51. The disk 1' is preferably mounted on the shaft 2 by the metallic hub 52 which is suitably fastened to the disk 1' as by the bolts 54; the disk 12 being provided with a suitable aperture 12' 80 through which the shaft 2 extends.

The shaft 9^a carrying the gear wheel 27 extends rearwardly through the disk 12, but the other shafts 9^b, 9^c, and 9^d journaled in their respective bearings 10 in the disk 85 proper 1' do not extend beyond the disk 12, so that the said disk can be conveniently rotated close to the bed box or like mounting 55 as illustrated in Fig. 3.

The sprocket wheel 28, preferably of insulating material, is mounted on the shaft 9^a, and similar sprocket wheels 29, 30 and 31 are mounted on the shafts 9^b, 9^c, 9^d, respectively, between the disks 1' and 12. The sprocket chain 32 connects the wheels 28, 90 29, etc. The said wheels are preferably of varying size or number of sprockets, as illustrated, so that the rotation imparted through the sprocket wheel 28 and chain 32 will drive the shafts 9^a, 9^b, etc., at varying 100 rates, thereby rotating the light tubes 7^a, 7^b, etc., at varying speeds so as to produce any desired light effect. The disks 8^a, 8^b, etc., on which the tubes 7^a, 7^b, etc., are mounted, are of fiber or like insulating material, each 105 having a circumferential band or strip 35 of metal with which one of the brushes 36 carried on the disk 1' contacts. The light-tubes 7^a, 7^b, etc., are preferably fastened, as by the wires 37 to the carrying arms 38, 110 respectively, each provided with a metal sleeve 39 which fits over the end of one of the shafts 9^a, 9^b, etc., (see Fig. 3). The carrying arms 38 are fastened rigid with the disks 8^a, 8^b, etc., preferably by the set screws 115 40. These carrying arms 38 vary somewhat in form, as shown in Fig. 1, each however, being provided with the counterweight 41 having a slotted arm 42 fastened to the carrying arm 38 by a set screw 43, so that 120 the position of the counterweight may be varied to accurately balance any light-tube as 7^b which may be attached to the carrying arm.

Each light-tube, as 7^a, is provided with a 125 wire 44 connecting one of its poles 45 with a circumferential metallic strip 35 on the disk, as 8^a; and with another wire 46 connecting its opposite pole 47 with the metallic disk hub 11 or shaft, as 9^a. The wires 48 con- 130

nect each of the spring brushes 36 with the fixed metallic hub 10 of the adjacent shaft, as 9^b carrying the adjacent tube as 7^b, to which current is connected from the hub 10 through the shaft 9^b and wire 46. The current after passing through the tube 7^b traverses the wire 44, contact surface 35, brush 36 and wire 48 leading to the next tube 7^c, and thence in a similar manner through the tube 7^a, and 7^d, which is connected by a wire 46' to the conducting surface or strip 35 of the disk 8^d.

The wire or metallic strip 49 leads from the brush 36 in contact with the disk 8^d to the brush 36 in contact with the disk 1' mounted on the shaft 2. The shaft 2 is connected in any suitable manner as by the wire N electrically joined to the bearing 3' to a source of current. The circuit may be continued in any preferred fashion to a suitable vibrator or equivalent device (not illustrated) by which the peculiar interrupted current necessary to illumine the Geissler tubes employed is produced, the wires M', N' illustrated in Fig. 4 being understood as leading, one of them, from the secondary coil of such a vibrator. I prefer, however, to provide the return wire M electrically joined to the metallic sprocket chain 21 by the bearing bracket 19, countershaft 18 and sprocket wheel 20. The metallic circuit is then continuous through the metal faces 23, 23', of the insulating gear wheel 22 and sprocket chain 26 to the metallic sprocket wheel 27 and shaft 9^a. The current then passes from the shaft 9^a through the metal hub 11 and wire 46 to the first light tube 7^a and thence through the other tubes as described above.

The relative numbers of gear teeth 24 and 40 25 on the double gear wheel 22, 22' are so arranged that when the shaft 2 is rotated carrying with it the disk frame 1 the sprocket wheel 22' will have a rotation differing from that of the shaft 2. The shaft 45 9^a and each of the shafts 9^b, 9^c, and 9^d is then rotated through the sprocket chain 26, wheels 27 and 28 and sprocket chain 32. The rates of rotation of each of the tubes 50 55 may be arranged and varied at will by varying the size of the particular sprocket wheel 27, or 29, etc., mounted on its shaft 9^a or 9^b, etc. The rate of rotation of all the tubes moreover is conveniently regulated by changing either the number of sprocket 60 65 teeth 23, 24 or the effective sizes of any one of the sprocket wheels 14, 16 or 20. I therefore provide a convenient mechanism by which the light tubes are simultaneously revolved and rotated, the said mechanism 65 serving as part of the conducting electric circuit of said tubes, and being capable further of slight adjustment or changes of varying the rate of rotation of all the tubes and also their relative rates of rotation. I therefore provide means for obtaining not

only a novel light effect due to the revolution and mutual rotation of the light-tubes, but also an infinite number of variations in the lighting effect by adjustment in the mechanism.

70

What I claim is:

1. A device of the character described comprising a plurality of electric light-tubes, a rotatable support for each tube, a frame in which said supports are journaled, and actuating mechanism forming part of the electric circuit of said tubes and co-operating with said frame to simultaneously rotate the same and said tube supports.

80

2. A device of the character described comprising a plurality of Geissler tubes, a rotatable support for each tube, a frame in which said supports are journaled, and actuating mechanism co-operating with said frame to simultaneously rotate the same and said supports, said actuating mechanism forming part of the electric circuit of said tubes.

85

3. A device of the character described comprising an insulating frame, an insulating support and a conducting shaft carrying the same and journaled in said frame, and a light carried by said support, in combination with a second conducting shaft carrying said frame, an electrical connection between said second shaft and said light, and another conductor connected to said conducting shaft journaled in said frame, and means for independently rotating said frame and support.

90

4. A device of the character described comprising an insulating frame, an insulating support and a conducting shaft carrying the same and journaled in said frame, and a light carried by said support, in combination with a second conducting shaft carrying said frame, an electrical connection between said second shaft and said light, an insulating gear wheel journaled on said 105 shaft carrying said frame, and conducting gearing connections between said gear wheel and said shaft journaled in said frame.

105

5. A device of the character described comprising an insulating frame, a plurality 115 of insulating disk supports, a conducting shaft carrying each support and journaled in said frame; an electrical connection carrying current to one of said shafts, a light carried by each shaft and provided with a 120 conductor communicating therewith, another conductor leading from each light to the shaft of another light, a return conductor leading from one of the other lights, and means for simultaneously rotating said 125 frame and said shafts journaled therein.

6. A device of the character described comprising an insulating frame, a plurality of insulating supports, a conducting shaft carrying each support and journaled in 130

4
said frame, an electrical connection carrying current to one of said shafts, a light carried by each shaft and provided with a conductor communicating therewith, each 5 of said supports having a continuous conducting surface and a conductor leading from its light thereto, a brush carried by said frame in contact with each of said surfaces and provided with an electric connection 10 to another of said shafts, a brush on said frame in contact with one of said surfaces connected to the return circuit, and means coöperating therewith for simultaneously rotating said frame and each of said 15 shafts journaled therein.

7. A device of the character described comprising an insulating frame, a metallic driving shaft carrying the same, a plurality of electric lights, a shaft carrying each light 20 and journaled in said frame, an electric circuit including said lights and a conductor communicating with said driving shaft, an insulating sprocket wheel journaled on said driving shaft, and provided with a metallic 25 surface, a metallic driving connection in electrical contact with said surface on said sprocket wheel, and each of said shafts journaled in said frame, a driving connection between said surface and said driving 30 shaft but insulated therefrom, and an elec-

trical circuit leading through said conducting surface and said first mentioned driving connection and one of aforesaid journaled shafts to aforesaid electric light circuit.

8. A device of the character described 35 comprising an insulating frame, a plurality of electric lights, metallic shafts carrying said lights and journaled in said frame, a conducting gear wheel mounted on one of said shafts, a metallic driving shaft carrying 40 said frame, an insulating gear wheel mounted on said driving shaft and provided with a conducting surface, a sprocket chain in contact with said surface connecting said gear wheel and aforesaid conducting gear 45 wheel, an actuating connection between said shaft on which said conducting gear wheel is mounted and another shaft journaled in said frame, an electrical circuit including said lights and said driving shaft, and a re- 50 turn metallic circuit including said metallic surface, sprocket chain and conducting sprocket wheel.

In testimony whereof I the said HANNIBAL A. KUNITZ have hereunto set my 55 hand.

HANNIBAL A. KUNITZ.
